UNITED STATES PATENT OFFICE

JAMES O. LEWIS, OF TULSA, OKLAHOMA

PULSING MACHINE

Application filed June 8, 1929. Serial No. 369,513.

My invention relates to repressuring of oil sands to stimulate flow of oil to producing wells, and more particularly to apparatus for so controlling supply of the different pressure mediums, such as air and natural gas to the sands, as to preclude formation of a combustible mixture of said mediums within the service equipment and flow lines.

It is well known by those experienced in this art that gas is more readily soluble in oil than in air, but that air has a greater propelling effect on oil in the sands, and that consequently a mixture of air and gas would be more effective for repressuring if such mixture could be employed. However, such a mixture is dangerous unless the proportions of air and gas are kept outside the ratio at which they form a combustible mixture, due to a tendency of explosion should the combustible mixture become ignited through sparks resulting from contact of pieces of metal or flinty substances in the oil with the walls of the apparatus.

While air and natural gas are of different specific gravities, they may be conducted through a conduit in alternate slugs and under high pressure without substantial mixture except within limited areas at the junctions of the slugs, and by so employing these different mediums I am able to effect a more advantageous repressuring than with either medium alone and with slight danger of explosion due to ignition of a mixture of the two.

It is, therefore, the principal object of my invention to so employ both air and gas that both may be utilized for repressuring oil sands without danger of explosion and in accomplishing this object I have provided apparatus whereby the air and gas may be delivered in alternate slugs through the same conduit under automatic control, the accompanying drawings illustrating a preferred form of apparatus embodying my invention:

Fig. 1 is a diagrammatic view of the apparatus in combination with air and gas compressors, supply lines and pressure wells.

Fig. 2 is an enlarged central vertical section of the apparatus.

Fig. 3 is a plan view of the apparatus.

Referring in detail to the drawings:

1 and 2 designate compressors of conventional type adapted for receiving air and gas through the respective intakes 3 and 4; the air intake 3 being preferably filtered by means not shown, and the gas intake 4 connected with the casing heads of oil producing wells or with natural gas wells (not shown).

5 designates a feed line through which pressure medium is conducted to one or more wells 6 for distribution to the oil sands for repressuring, and 7 a separate line for conducting the medium to another well or group of wells indicated by the well 8 for repressuring sands serving a different group of producing wells (not shown) at a distance from that served by the well 6.

9 designates control apparatus, designated a pulsing machine, whereby charges of air and gas are delivered alternately and in continuous flow to both groups of wells, and which embodies the following details of construction:

10 and 11 designate duplicate four-way fittings, the lower branches of which are closed by plates 12 and 13 attached to the flanges 14-15 of the fittings by bolts 16-17, and made air or gas-tight by packing 18-19; the fittings 10 and 11 forming the base elements upon which the pulsing machine may be supported on a suitable foundation 20.

The branch 21 of the fitting 10 connects with the line 5 leading to the pressure well 6 through a flange connection 22 made air and gas-tight by conventional packing. Branch 24 communicates with the branch 25 of the fitting 11 through an air and gas-tight connection indicated by the flanges 26-27, the bolts 28 and packing 29. The branch 31 constitutes a dead end, closed by a plate 32 having air and gas-tight connection with the branch through the flanges 33-34, bolts 35 and packing 36. The branches 38-39 of the respective fittings 10-11 rise therefrom, and mounted on said branches are heads 40 and 41 which are duplicates of each other in construction, but connected respectively with the separate air and gas compressors.

1 and 2, as presently disclosed, the respective branches being provided with flanges 42-43, seating flanges 44-45 of the headers 40-41, and connected thereto by bolts 46-47.

5. Interposed between the branch and header flanges are valve plates 48-49 having central, vertical ports 50-51; the connections, including the valve plates, being made air and gas-tight by packing (not shown).

10. Supported on the upper ends of the headers 40-41 are four-way fittings 52-53 which are duplicates of the base fittings 10-11, and therefore duplicates of each other, the lower branches 54-55 of which are attached to the 15 respective headers by bolts 56-57 that extend through flanges 58-59 and 60-61 on the fittings and headers, respectively.

Interposed between the fitting and header flanges and attached thereto by the bolts 20 56-57 are valve plates 62-63 which are duplicates of the lower valve plates 50-51, and have ports 64-65 registering with the ports 50 and 51 in said lower plates.

The branch 66 of fitting 52 is dead ended 25 by a plate 67 attached to a flange 68 on the fitting by bolts 69. Branch 71 of the fitting 53 communicates with the conduit 7 leading to the pressure well 8 through a gas and air-tight connection indicated by the flanges 30 72-73 and bolts 74.

The branches 76-77 of the upper fittings 52-53 communicate with each other through an air and gas-tight connection indicated by the flanges 78-79 and bolts 80.

35. Attached to the upper vertical branches 82-83 of said upper fittings are plates 84-85 having air and gas-tight connection with their supporting branches through flanges 86-87, bolts 88 and packing 89.

40. Extending through stuffing boxes 90-91 on the plates 84 and 85, and concentrically through the ports 64-65 and 50-51 in the valve plates 62-63 and 48-49, respectively, at the top and bottom of the headers 40-41, 45 are valve stems 92 and 93, attached by nuts 94 at their upper ends to a cross-head 95 having guided mounting on the reduced ends 96-97 of posts 98 and 99, having threaded mounting in the respective cover 50 plates 84-85; the posts having stops 100-101 for limiting downward movement of the cross-head under tension of springs 102-103, attached to the cross-head and to the upper fittings 52-53, preferably by 55 hooks 104-105, attached to the flanges 68-72 by bolts 69 and 74.

Fixed to the reduced ends 96 and 97 of said posts 98 and 99 are upper stop members 106-107 which limit upward movement of the cross-head against the tension of said springs under influence of a pneumatic lift consisting of a rod 108 attached to the cross-head by nuts 109 and extending through a stuffing box 110 on a diaphragm housing 111 65 to the interior of said housing where it is

connected with a flexible diaphragm 112 by nuts 113. The diaphragm is held to the housing member by flange bolts 114 in the usual manner to make the diaphragm chambers air and gas-tight, and the housing is 70 attached to the upper fitting plates 84-85 by bolts 115.

Communicating with the lower diaphragm chamber 116 through a port 117 is the line 118 from a pressure controller 119 having 75 communication with a constant supply of pressure medium, preferably the flow line from the air or gas compressor 1 or 2, through a line 144, as presently more specifically mentioned, the controller being of a conventional 80 type, time controlled to supply pressure medium to the diaphragm at regular intervals which may be determined by an adjustment with which such controllers are equipped.

Referring back to the header elements 85 40-41 of the pulsing apparatus, 120-121 designates branches opening to the respective headers through ports 122-123 and connected respectively with the lines 124-125 leading from the air and gas compressors 90 by the usual air and gas-tight connections indicated to be the flanges 126-127-128-129, the bolts 130 and the packing 131, so that when the apparatus is in operation air is delivered to the header 40 from the compressor 1, and gas to the header 41 from the compressor 2. The headers are preferably in the nature of four-way unions with the branches 132-133 dead ended by plates 134-135 attached to flanges 136-137 by bolts 138, and 95 provided with the usual packing 139.

Referring again to the mechanism controlling flow of air and gas through the pulsing machine 9, 140-141 designate reversely arranged valves, preferably of castellated 105 type, fixed on the stem 92 and adapted for such cooperation with the valve ports 64 and 50 that when one port is open the other is closed, and vice versa, Fig. 2 illustrating the upper port open and the lower port closed 110 so that air entering the header 40 through port 122 is precluded from passing into the fitting 21 for delivery into line 5 leading to the well 6, but may pass through the fitting 52 and fitting 53 into the line 7 leading to 115 the well 8. Fixed to the other valve stem 93 are similar valves 142-143 arranged reversely relative to each other, and to the valves on the stem 92, so that when the valves are in the position indicated in Fig. 2 and air is flowing to the wells 8, gas entering the header 41 through port 123 is precluded from entering the fitting 53 to mix with air, but may pass through port 51, fitting 11, fitting 10, and line 5 to the well 6.

Assuming the apparatus to be constructed and assembled as described, and starting with the valves of the pulsing machine in the position indicated in Fig. 2, i. e., with the controller 119 supplying gas or air under pres- 120 125

sure to the diaphragm 112 and with the compressors in operation, air is delivered through the header 40, through the open valve port 64 and through the upper fittings into line 5, through which it is delivered to the well 7, through which it is delivered to the well 8, and gas from the compressor 2 is delivered through the header 41, open valve port 51 and the communicating fittings into line 5, through which it is delivered to the well 6; the air and gas flowing through the different lines being kept separate by the valve mechanism within the pulsing machine. The air and gas continue to flow to the respective wells through the separate lines for a period determined by adjustment of the controller 119, but at the end of the set interval the controller cuts off supply of air to the diaphragm, and the springs 102-103 retract the cross-head 94, shifting the valve stems to reverse arrangement of the valves in the separate headers.

Upon reversal of the valve seatings, air admitted to header 40 through port 122 will then flow through the port 50 to fitting 21 and line 5 and to the well 6, and gas entering the header 41 through port 123 will flow through port 65 and fitting 53 to line 7, through which it is delivered to the well 8.

Thus the air and gas are delivered continuously through one or the other of the lead lines to one or the other pressure wells without intermingling in the control apparatus or lines, the periods of alternate flow of the different mediums being determined by adjustment of the regulator, but after adjustment continuing in such alternation and for like periods without necessitating manual control.

Having thus described my invention, what I claim and desire to secure by Letters Patent is:

1. In apparatus of the character described, a plurality of spaced headers having parallel individual inlets, a common outlet on one end of the headers, a common outlet on the opposite ends of the headers, and valve means in the headers for selectively directing flow of fluid from a header to either of the outlets.
2. In apparatus of the character described, a plurality of spaced headers having individual inlets, a common outlet connected to one end of the headers, a valve plate interposed between each of the headers and said outlet, a common outlet connected to the opposite ends of the headers, a valve plate interposed between each of the headers and said last-named outlet, a double-acting valve in each header adapted to cooperate with the valve plates, and means for actuating the valves for selectively directing flow of fluid from a header to either of the outlets.
3. In apparatus of the character described, a plurality of spaced headers having individual inlets, a common outlet connected to one end of the headers, a valve plate inter-

posed between each of the headers and said outlet, a common outlet connected to the opposite ends of the headers, a valve plate interposed between each of the headers and said last-named outlet, a single stem extending concentrically through the plates of each header, a pair of valves fixed on each stem in spaced relation and adapted to respectively cooperate with said plates, and means for actuating said stem to operate the valves.

4. In apparatus of the character described, a plurality of spaced headers having individual inlets on a common side of the headers, a common outlet on one end of the headers, a common outlet on the opposite ends of the headers, and valve means in the headers for selectively directing flow of fluid from a header to either of the outlets.

5. In apparatus of the character described, a plurality of spaced headers, each header having individual inlets on opposite sides thereof, flow lines for supplying fluid to the headers, means for connecting the flow lines to either side of the headers, a common outlet on one end of the headers, a common outlet on the opposite ends of the headers, and valve means in the headers for selectively directing flow of fluid from a header to either of the outlets.

In testimony whereof I affix my signature. 25
JAMES O. LEWIS.
